UNITED STATES PATENT OFFICE.

PHILLIP J. BORNSTEIN, OF SEATTLE, WASHINGTON.

DESIGN FOR A VASE.

No. 38,716.

Specification for Design.

Patented Aug. 6, 1907.

Application filed June 18, 1907. Serial No. 379,671. Term of patent 7 years.

To all whom it may concern:

Be it known that I, PHILLIP J. BORNSTEIN, a citizen of the United States of America, and a resident of the city of Seattle, in the county of King and State of Washington, have invented a new, original, and ornamental Design for Vases, of which the following is a specification, reference being had to the accompanying drawing, forming a part thereof.

The figure is a view in perspective of a vase, showing my new design.

I claim:

The ornamental design for a vase, as shown.

PHILLIP J. BORNSTEIN.
